(57) CLAIM

The ornamental design for a hair cover protector with interior pocket, as shown and described.

DESCRIPTION

FIG. 1 is a perspective view of a hair cover protector with interior pocket;

FIG. 2 is a front view thereof;

FIG. 3 is a left side view thereof;

FIG. 4 is a back view thereof;

FIG. 5 is a right side view thereof;

FIG. 6 is a top view thereof;

FIG. 7 is a bottom view thereof;

FIG. 8 is a perspective view thereof, as it may be positioned on a person's head;

FIG. 9 is a perspective view thereof; and,

FIG. 10 is a perspective view thereof shown in a different configuration.

The ribbon and pattern drawn by broken lines along the top of the article depict elements of the hair cover protector with interior pocket that form no part of the claimed design. The partial human figure drawn in broken lines in FIGS. 8-10 is environmental subject matter included to show the article in a position of use and forms no part of the claimed design.

1 Claim, 8 Drawing Sheets
